(57) **CLAIM**

The ornamental design for a discharge device, as shown and described.

DESCRIPTION

FIG. 1 is a perspective view of a discharge device embodying our new design;

FIG. 2 is a front view thereof;

FIG. 3 is a back view thereof;

FIG. 4 is a left view thereof;

FIG. 5 is a right view thereof;

FIG. 6 is a top view thereof; and

FIG. 7 is a bottom view thereof; and,

FIG. 8 is a cross-section view along line 8—8 of the discharge device of FIG. 4.

The broken lines shown in the drawings are for illustrative purposes only and form no part of the claimed design.
